[57] **CLAIM**

The ornamental design for a golf club, as shown and described.

DESCRIPTION

FIG. 1 is a perspective view of a golf club showing my new design;

FIG. 2 is an enlarged fragmentary front view of the head of the golf club showing my new design;

FIG. 3 is a rear elevational view of the golf club head of FIG. 2;

FIG. 4 is a right end elevational view of the golf club head of FIG. 2, the left end view being a mirror image thereof;

FIG. 5 is a perspective view of a modified embodiment of a golf club showing my new design;

FIG. 6 is an enlarged fragmentary front view of the head of the modified golf club of FIG. 5;

FIG. 7 is a rear elevational view of the golf club head of FIG. 6; and

FIG. 8 is a right end elevational view of the golf club head of FIG. 6, the left end view being a mirror image thereof with the shaft removed.
